UNITED STATES PATENT OFFICE

164,587

SPECTACLE CASE

Robert J. Marks, Castro Valley, Calif.

Application November 27, 1950, Serial No. 13,134

Term of patent 3½ years

(Cl. D57—1)

To all whom it may concern:

Be it known that I, Robert J. Marks, a citizen of the United States and a resident of Castro Valley, county of Alameda, State of California, have invented a new, original, and ornamental Design for a Spectacle Case, of which the following is a specification, reference being had to the accompanying drawing, forming part hereof.

I claim:

The ornamental design for a spectacle case, substantially as shown.

ROBERT J. MARKS.
